UNITED STATES PATENT OFFICE.

ARTHUR MATTERN, OF WILLIAMSPORT, PENNSYLVANIA.

LIQUID-SPRAYER.

1,229,771.

Specification of Letters Patent. Patented June 12, 1917.

Application filed January 27, 1917. Serial No. 144,914.

To all whom it may concern:

Be it known that I, ARTHUR MATTERN, a citizen of Germany, residing at Williamsport, in the county of Lycoming, in the State 5 of Pennsylvania, have invented certain new and useful Improvements in Liquid-Sprayers, of which the following is a specification.

This invention relates to improvements in liquid sprayers and one object is to provide 10 a device of this class adapted particularly for use in spraying or sprinkling clothes, flowers, etc. A further object is to provide a device of this class that may be adjusted to make a fine or coarse spray as desired. A 15 further object is to provide a device of this class that is simple in construction, efficient in operation and cheap to manufacture.

With the foregoing and other objects in view the invention consists in the combination 20 and arrangement of parts to be herein-after fully described in this specification, pointed out in the appended claim and illustrated in the accompanying drawing which forms a part of the specification and in 25 which—

Figure 1 is a side elevation, partly in section, of one embodiment of my invention.

Fig. 2 is an enlarged fragmentary sectional view detailing the construction of the 30 spray-adjusting medium.

Fig. 3 is a top plan view of Fig. 2.

Like reference characters denote corresponding parts throughout.

The reference numeral 1 denotes a liquid 35 container of any preferred size or shape and made of any suitable material and the same is formed with an orifice 2 in its top 3 through which its liquid contents are introduced. A tube or pipe 4 extends from a 40 point a short distance above the bottom 5 of the container to the top 3 thereof, the upper end of said tube being threaded for engagement with a threaded opening in the said container top, the bottom end of said tube 45 being closed except for a small orifice 6 in alignment with a similar orifice formed in the terminal screw cap 7 with which said tube is provided. The bottom 5 of the container is removably carried by that member. 50 to permit the installation of the said tube 4.

The tube 4, further, at its upper end is provided with the partition or seat 8 formed with a tapered opening 9 to receive the

pointed stem 10 of the needle valve 11, said stem 10 being of substantially smaller diameter than the tube 4 and formed with a transverse port 12 extending therethrough and communicating with the port 13 that extends longitudinally of said needle valve above the said port 12. The needle valve, 60 further, is threaded exteriorly for engagement with the interiorly threaded upper end of said tube 4.

A lug or ear 14 is carried by the container top 3 and to the said lug a tube 15 is fulcrumed the larger end 16 thereof forming a mouthpiece and the smaller end 17 thereof resting upon said needle valve 11 at a point adjacent the port 13, said tube 15 being yieldingly retained in engagement with said valve through the medium of a contractile spring 18 connecting said tube and the container top 3. When the container 1 is partly filled with a liquid the same may be caused to rise through the tube 4 and needle valve 11 by placing the larger end of the tube 15 in the mouth and forcing air therethrough, the rising liquid being passed in the form of a spray through the atmosphere. By raising or lowering the needle valve in its seat and increasing or diminishing the size of the opening therein a coarse or fine spray, as desired, may be obtained.

What is claimed is:—

In a liquid sprayer, a liquid container having an orifice in its top, a tube having one of its ends in engagement with an apertured portion of said top and extending into the interior of said container, closing means arranged in the upper end of said tube for varying the size of the opening therein, a tubular member fulcrumed upon said container top and having one of its ends projected over said closing means, and a spring connecting said container top and tubular member whereby one end of the latter is yieldingly retained in engagement with said closing means.

In testimony that I claim the foregoing as my own I have hereto affixed my signature 100 in the presence of two subscribing witnesses.

ARTHUR MATTERN.
